UNITED STATES PATENT OFFICE.

WALTER F. STIMPSON, OF DETROIT, MICHIGAN, ASSIGNOR TO ESTELLE H. STIMPSON, OF DETROIT, MICHIGAN.

DESIGN FOR A SCALE-FRAME.

45,661.

Specification for Design.

Patented Apr. 21, 1914.

Application filed November 24, 1913. Serial No. 802,834. Term of patent 14 years.

To all whom it may concern:

Be it known that I, WALTER F. STIMPSON, a citizen of the United States of America, residing at Detroit, in the county of Wayne and State of Michigan, have invented a certain new, original, and ornamental Design for a Scale-Frame, of which the following is a specification, reference being had therein to the accompanying drawings, forming part thereof, in which—

Figure 1 is a perspective view of a scale, showing my new design; and Fig. 2 is a side elevation thereof.

I claim:

The ornamental design for a scale frame, substantially as shown.

WALTER F. STIMPSON.

Witnesses:

WM. J. BELKNAP,
JAMES P. BARRY.
